UNITED STATES PATENT OFFICE.

EUGEN GALITZENSTEIN AND MARTIN MUGDAN, OF NUEREMBERG, GERMANY, ASSIGNEES TO CONSORTIUM FÜR ELEKTROCHEMISCHE INDUSTRIE G. M. B. H., OF NUEREMBERG, GERMANY.

PROCESS FOR THE MANUFACTURE OF ORGANIC ACIDS, ESPECIALLY ACETIC ACID.

1,179,420.

No Drawing.

Specification of Letters Patent.

Patented Apr. 18, 1916.

Application filed July 25, 1913. Serial No. 781,188.

To all whom it may concern:

Be it known that we, EUGEN GALITZENSTEIN, subject of the Emperor of Austria-Hungary, and MARTIN MUGDAN, subject of the German Emperor, residing at Nuremberg, Bavaria, Germany, have invented certain new and useful Improvements in Processes for the Manufacture of Organic Acids, Especially Acetic Acid, of which the following is a specification.

The reaction between acetaldehyde and oxygen only takes place very slowly under ordinary conditions so that it may be considered as impossible to prepare acetic acid technically by the interaction of oxygen and acetaldehyde without special precautions. In order to carry out this reaction it has therefore been proposed to employ oxygen under pressure. Such a process is not only attended with considerable difficulties in working, but also with danger of explosion.

Another process for transforming acetaldehyde to acetic acid by oxygen has been described in British Patent No. 17424 of 1911 (Johnson). In this process the acetaldehyde could be rapidly oxidized only if excess of acetic acid were previously added thereto or excess of acetic anhydrid, trichlor-acetic acid, etc. Moreover in this process it was necessary to operate at a temperature higher than ordinary atmospheric temperatures.

According to the present invention it has been found that it is possible to attain a transformation of acetaldehyde to acetic acid by means of oxygen without pressure at ordinary temperatures and in such manner that the reaction proceeds quite fairly, when small quantities of manganese compounds are added to the aldehyde as catalysts. The action of the manganese compounds is quite specific. The initial absorption of oxygen by the acetaldehyde can indeed be accelerated to some extent also by compounds of other metals such as for instance of chromium, vanadium, iron, cerium, uranium, etc., but in this case there always result considerable quantities of per-acetic acid according to the equation

This acid is capable of decomposing with the aldehyde still present with explosive rapidity. However, in contradistinction to

the above mentioned catalysts, manganese compounds possess the property not only of catalytically accelerating absorption of oxygen by acetaldehyde, but also the reduction to acetic acid of the per-acetic acid first formed, according to the equation

Thus it is only by the aid of manganese compounds that it is possible to oxidize acetaldehyde to acetic acid by oxygen smoothly and without danger.

Example: A vessel of pure aluminium provided with stirring gear and a cooling jacket is charged with 300 kilos of pure acetaldehyde and 2 kilos of powdered manganese acetate, and a current of dry oxygen is led in. By the action of the oxygen the manganese acetate first dissolves in the acetaldehyde giving a brown coloration; this solution now energetically absorbs oxygen. The heat of reaction which is evolved is absorbed by vigorous external cooling by means of running water. The only by-product is a small quantity of carbon di-oxid which is blown off either from time to time, or continuously. The absorption of oxygen is complete after from ten to twenty hours. In this way a high percentage acetic acid is directly obtained which can be separated by distillation both from the small quantity of unchanged aldehyde and from the manganese compound.

Other compounds of manganese may be employed instead of manganese acetate with the same success. For example manganese formate, butyrate, benzoate, lactate or potassium permanganate, calcium permanganate and various other compounds. In all these cases a brown solution of manganese compound in acetaldehyde is produced first in which solution we believe the manganese compound to be in colloidal form. Gases containing oxygen such as atmospheric air may be used instead of pure oxygen, but in this case care must be taken that the acetaldehyde which is carried away by the unabsorbed portion of the gas *e. g.* the nitrogen) is recovered in suitable absorption apparatus.

It will be understood that in carrying out this process, instead of using pure aldehyde treated with manganese compounds, the aldehyde may also be employed dissolved

in other liquids, for example acetic acid. Finally the manganese compounds may also be employed in conjunction with other catalysts such as for example compounds of 5 chromium or vanadium which accelerate the absorption of oxygen *i. e.* the primary formation of the per-acid.

Beyond employing the manganese compounds in the powdered form, or adding 10 them dissolved in acetaldehyde, it is also possible to employ colloidal solutions of manganese compounds in suitable solvents for example in acetaldehyde itself. This reaction may also be employed in some cases 15 to the oxidation of other aldehydes to their corresponding acids.

We declare that what we claim is:

1. Process for the manufacture of organic acids from the corresponding aldehydes, 20 comprising oxidizing said aldehydes with oxygen in presence of a manganese compound as catalyst.

2. Process for the manufacture of organic acids from the corresponding aldehydes, 25 comprising oxidizing said aldehydes with oxygen under stirring in presence of a manganese compound as catalyst.

3. Process for the manufacture of acetic acid, comprising oxidizing acetaldehyde by 30 a gas containing oxygen in the presence of a manganese compound as catalyst.

4. Process for the manufacture of acetic acid, comprising oxidizing acetaldehyde by 35 a gas containing oxygen under stirring in the presence of a manganese compound as catalyst.

5. Process for the manufacture of acetic acid, comprising oxidizing acetaldehyde with 40 oxygen in the presence of a manganese compound as catalyst.

6. Process for the manufacture of acetic acid, comprising oxidizing acetaldehyde by 45 oxygen in presence of a manganese compound existing in solution as catalyst.

7. Process of manufacturing acetic acid, comprising oxidizing acetaldehyde with oxygen in presence of a manganese compound existing in the solution in colloidal 50 form as catalyst.

8. Process of manufacturing acetic acid, comprising adding manganese acetate to 55 acetaldehyde and passing oxygen through the mixture.

9. Process of manufacturing acetic acid, comprising oxidizing acetaldehyde with 60 oxygen in the presence of a manganese compound as catalyst and in presence of another metal compound.

10. Process of manufacturing acetic acid, comprising oxidizing acetaldehyde with

oxygen at atmospheric pressure in the presence of a manganese compound as catalyst.

11. Process for the manufacture of acetic acid comprising introducing a gas containing oxygen into acetaldehyde containing a 65 manganese compound as catalyst and recovering any acetaldehyde carried over by the unabsorbed gas.

12. Process of manufacturing acetic acid, comprising oxidizing acetaldehyde with 70 oxygen in the presence of a manganese compound as catalyst and distilling the resulting product to free it from any unchanged acetaldehyde and from said manganese compound.

13. Process for manufacturing acetic acid, comprising oxidizing acetaldehyde with oxygen in presence of a solvent for acetaldehyde and in presence of a manganese compound as catalyst. 80

14. Process for manufacturing acetic acid, comprising oxidizing acetaldehyde with oxygen in presence of acetic acid as solvent and of a manganese compound as catalyst.

15. The process of manufacturing acetic 85 acid which comprises causing acetaldehyde to interact with oxygen at atmospheric pressure and at ordinary temperatures in the presence of a manganese compound as catalyst.

16. The process for the manufacture of acetic acid, which comprises introducing oxygen into acetaldehyde contained within a water cooled vessel in the presence of a manganese compound as catalyst, and agitating said acetaldehyde. 90

17. The process for the manufacture of an organic acid from the corresponding aldehyde, which comprises causing said aldehyde to interact with oxygen in presence of a manganese compound as catalyst, at ordinary temperatures.

18. The process for the manufacture of acetic acid, which comprises causing acetaldehyde to interact with oxygen in presence of a manganese compound existing in solution as catalyst, at ordinary temperatures.

19. The process of manufacturing acetic acid comprising mixing acetaldehyde with manganese acetate and passing oxygen through the mixture at ordinary temperatures.

In testimony whereof we affix our signatures in presence of two witnesses.

EUGEN GALITZENSTEIN.
MARTIN MUGDAN.
